(57) **CLAIM**

The ornamental design for novelty eyeglasses with interchangeable caps, as shown and described.

DESCRIPTION

FIG. 1 illustrates an isometric top front view of novelty eyeglasses with interchangeable caps showing my new design;

FIG. 2 illustrates another isometric top front view thereof;

FIG. 3 illustrates an isometric bottom front view thereof;

FIG. 4 illustrates another isometric bottom front view thereof;

FIG. 5 illustrates an isometric bottom rear view thereof;
FIG. 6 illustrates another isometric bottom rear view thereof;

FIG. 7 illustrates a front view thereof;

FIG. 8 illustrates a rear view thereof;

FIG. 9 illustrates a right side view thereof;

FIG. 10 illustrates an enlarged partial view of the portion identified as 10 in FIG. 9;

FIG. 11 illustrates a left side view of the novelty eyeglasses with interchangeable caps;

FIG. 12 illustrates an enlarged partial view of the portion identified as 12 in FIG. 11;

FIG. 13 illustrates a top view of the novelty eyeglasses with interchangeable caps;

FIG. 14 illustrates a bottom view thereof;

FIG. 15 illustrates another isometric top front view of the design of FIG. 1, but shown with one of the interchangeable caps removed;

FIG. 16 illustrates another isometric top front view thereof;

FIG. 17 illustrates another isometric top front view thereof, but shown with the interchangeable cap on the right side of the frame;

FIG. 18 illustrates another isometric top front view thereof;

FIG. 19 illustrates another isometric top front view of the design of FIG. 1, but shown with both of the interchangeable caps removed;

FIG. 20 illustrates an enlarged partial view of the portion identified as 20 in FIG. 19;

FIG. 21 illustrates another isometric top front view of the design of FIG. 1, but shown with both of the interchangeable caps removed thereof;

FIG. 22 illustrates an enlarged partial view of the portion identified as 22 in FIG. 21;

FIG. 23 illustrates an isometric bottom front view of the design of FIG. 1, but shown with both of the interchangeable caps removed;

FIG. 24 illustrates another isometric bottom front view;

FIG. 25 illustrates an isometric bottom rear view thereof;

FIG. 26 illustrates another isometric bottom rear view thereof;

FIG. 27 illustrates a front view thereof;

FIG. 28 illustrates a rear view thereof;

FIG. 29 illustrates a right side view thereof;

(Continued)

FIG. 30 illustrates an enlarged partial view of the portion identified as 30 in FIG. 29;

FIG. 31 illustrates a left side view of the design of FIG. 1, but shown with both of the interchangeable caps removed; FIG. 32 illustrates an enlarged partial view of the portion identified as 32 in FIG. 31;

FIG. 33 illustrates a top view of the design of FIG. 1, but shown with both of the interchangeable caps removed;

FIG. 34 illustrates an isometric top front view of the interchangeable cap of FIG. 1 shown separately for completeness of illustration;

FIG. 35 illustrates another isometric top front view thereof;

FIG. 36 illustrates another isometric top front view thereof;

FIG. 37 illustrates another isometric top front view thereof;

FIG. 38 illustrates an isometric bottom front view thereof;

FIG. 39 illustrates another isometric bottom front view thereof;

FIG. 40 illustrates an isometric bottom rear view thereof;

FIG. 41 illustrates another isometric bottom rear view thereof;

FIG. 42 illustrates a front view thereof;

FIG. 43 illustrates a rear view thereof;

FIG. 44 illustrates a right side view thereof;

FIG. 45 illustrates an enlarged partial view of the portion identified as 45 in FIG. 44;

FIG. 46 illustrates a left side view of the interchangeable cap of FIG. 1 shown separately for completeness of illustration;

FIG. 47 illustrates an enlarged partial view of the portion identified as 47 in FIG. 46;

FIG. 48 illustrates a top view of the interchangeable cap of FIG. 1 shown separately for completeness of illustration; and,

FIG. 49 illustrates a bottom view thereof.
